UNITED STATES PATENT OFFICE

CHARLES SCHWEIZER, OF MAPLEWOOD, MASSACHUSETTS, ASSIGNOR TO AMERICAN HEATING COMPANY, OF BOSTON, MASSACHUSETTS, A CORPORATION OF MAINE.

FURNACE.

No. 889,976.

Specification of Letters Patent.

Patented June 9, 1908.

Application filed May 9, 1903. Serial No. 156,484.

To all whom it may concern:

Be it known that I, CHARLES SCHWEIZER, a citizen of the United States, residing at Maplewood, in the county of Middlesex and State of Massachusetts, have invented certain new and useful Improvements in Furnaces; and I do hereby declare the following to be a full, clear, and exact description of the invention, such as will enable others skilled in the art to which it appertains to make and use the same.

This invention relates to means for effecting complete combustion of fuel, and thus utilizing its full calorific capacity; and it consists in the constructions, combinations, and arrangements hereinafter described and claimed.

Broadly stated, the invention comprehends the principle of the admission of air to various parts of the construction to facilitate combustion.

More specifically, it comprehends a fire-box with means for shunting a portion of the products of combustion directly to the boiler, and a partition-wall in the rear of the fire-box provided with restricted passages therethrough, combined with means constructed to direct the products issuing from the fire-box upward into contact with the partition-wall above the passages therein, prior to their escape therethrough.

Further and more specific details will presently appear.

In the accompanying drawings: Figure 1 is a sectional elevation, partly broken away, showing a furnace constructed in accordance with my invention; Fig. 2 is a sectional view, partly broken away on the line $x-x$ of Fig. 1; Fig. 3 is a sectional view, partly broken away on the line $y-y$ of Fig. 1; and Fig. 4 is a detail view of one of the fire-bricks, used in the construction of the walls of the fire-box.

Referring to the drawings: A represents an ordinary type of tubular boiler, inclosed within any suitable form of brick setting. Beneath the forward end of the boiler is located a fire-box B, provided with the usual fire-door or doors b^2 . The two side walls of the fire-box are shown formed of hollow bricks or refractory blocks b^4 , b^{12} . The lower

bricks b^4 preferably form the lateral walls of the ash-pit b^5 below the grate b^6 . The bricks b^4 rest upon hollow foundation fire-bricks b^7 , which communicate with the outside atmosphere through openings b^8 , with each other through openings b^9 , and with the bricks b^4 by openings b^{10} , as clearly shown in Fig. 1. The ash-pit b^5 is provided with the usual ash-door b^{11} and draft-opening b^8 . Directly above and preferably resting upon the bricks b^4 are the fire-bricks b^{12} , openings b^{13} forming communication between the hollow interiors of the bricks b^4 and b^{12} .

Supported upon the tops of the fire-bricks is preferably one long, inverted, fire-brick, 65 hollow cradle-arch C, desirably formed in two sections C^2 held together by a suitable locking-joint, or otherwise, as desired; but it is obvious that, instead of one long cradle-arch, a number of shorter ones may be employed 70 to span the fire-box, and that, instead of being inverted, the arch or arches may be in the ordinary position. In the upper concave surface of the arch are apertures c^2 , and the lower portion of the arch is provided with 75 apertures c^3 , communicating with the interior of the hollow bricks b^{12} , and with other apertures c^4 communicating with the fire-box B.

The perforations c^2 in the arch are properly 80 spaced to permit access of the heat to the boiler from the fire-box, thus ever to keep the boiler warm at this end. If desired, the boiler may be arranged so that the curve of the arch will be somewhat removed therefrom to allow freer access of heat. It will be noted that the passages or perforations c^2 in connection with the passages c^4 , practically 85 form the arch into a series of spaced arches.

A duct or air-chamber D is arranged behind the fire-box in a vertical partition-wall I, which latter is located to the rear of a bridge-wall J; said duct communicating with the two adjacent foundation fire-bricks b^7 through pipes d. The air-duct D is thus furnished with air from the hollow interiors of the bricks b^7 ; but, if desired, the air-duct may be otherwise supplied with air, as by being open at each end to the outside atmosphere.

Supported upon the duct D are hollow, 100

spaced air-blocks E, provided with lateral perforations e, the blocks and the air-chamber communicating by an opening e². The air-blocks E may lie flat, or may be slanting, 5 or inclined forward, as the setting of the boiler may require; but they must always be arranged to leave restricted spaces or passages therethrough. The duct D and blocks E are preferably located in the partition-wall 10 I a short distance behind the bridge-wall J in furnaces where heavy firing is employed, which would tend to injure or destroy the bricks if placed nearer the fire-box; but, with light firing, it is obvious that the air-chamber 15 or duct and the hollow air-blocks may rest upon the top of the bridge-wall; all as the exigencies of the situations may require.

Above the boiler may be provided a bypass or escape-flue F. A deflector-plate or 20 shutter f, pivoted to the upper end of the boiler, provides means for either directing the heated gases from the chamber G, beneath the rear portion of the boiler through the boiler-tubes, or permitting them to pass 25 through the flue F directly to the chimney; it being understood that the shutter is open under ordinary steaming and closed only in case of emergency, to prevent increasing pressure within the boiler, or to obviate the 30 necessity of banking or drawing the fire. Analogous means to the shutter or deflector-plate, such as a valve, may be employed to subserve the same function.

In the operation of my invention, fire 35 being started upon the grate, the major portion of the heated gases passes over the bridge-wall J and is directed by the bridge-wall against the partition-wall I, from whence, recoiling and whirling, they are thoroughly 40 intermixed and a portion of the unconsumed products in the gases is consumed thereby; and thence escape through the restricted lateral passages between the blocks E, where they are intimately intermingled with air 45 supplied from the air-chamber D, thus securing the most favorable conditions for complete combustion of any unconsumed products in the hot gases, and actually effecting complete combustion of all the unconsumed 50 products in the gases; and it will be noted that in passing through the restricted passages the gases, commingled with the air, are compressed, as it were, this being an important step in effecting ideal combustion. 55 From the blocks E, the products of combustion pass into the chamber G beneath the boiler and then upward to and through the boiler-tubes to the chimney or smoke-flue H.

It will be noted that the bridge-wall J extends upward a sufficient distance to direct 60 and guide the products of combustion upward thereover and against the partition-wall I before they pass through the spaced

blocks E, so that the products will recoil from the partition-wall and, whirling, effect thorough intermingling and combustion of a portion of the unconsumed products in the gases reaching this point; thence the gases, compressed and mingled with the air, pass through the spaced blocks E, where a further 70 combustion of unconsumed products takes place.

The smaller portion of the heated gases passes directly upward from the fire-box into the spaced arches C, where they are intimately intermixed with hot air from the hollow side-walls to insure complete combustion. From the hollow arches the products issue through the apertures c² and flow around the boiler shell to the chimney H. 80 It will be understood that the air flowing through the hollow side-walls acts to reduce their temperature and prevent injurious over heating.

Having thus fully described my invention, 85 what I claim is:

1. In a boiler-furnace, the combination of a fire-box, means constructed to supply air for combustion, passages arranged to shunt a portion of the products of combustion directly from the fire-box to the boiler, air-passages disposed in the walls of the fire-box and provided with apertures arranged to permit admixture of air with such shunted portion of the products, spaced, hollow perforated blocks arranged in the path of the remaining products, and an air-pipe connecting said air-passages and spaced, hollow blocks, whereby air is intimately intermingled with such products during their passage through the 100 spaced blocks.

2. In a boiler-furnace, the combination of a fire box, means constructed to supply air for combustion, passages arranged to shunt a portion of the products of combustion directly from the fire box to the boiler, air-passages disposed in the walls of the fire-box and provided with apertures arranged to permit admixture of air with such shunted portion of the products, spaced, hollow perforated blocks arranged in the path of the remaining products, an air-distributing chamber extending beneath and communicating with the hollow blocks, and conduits connecting said air-passages and the said air- 115 distributing chamber.

3. In a boiler-furnace, the combination of a fire-box, means constructed to supply air for combustion, passages arranged to shunt a portion of the products of combustion directly from the fire-box to the boiler, air-passages disposed in the walls of the fire-box and provided with apertures arranged to permit admixture of air with such shunted portion of the products, a passage arranged 120 to lead the remaining products from the fire- 125

box through the boiler-tubes and along the boiler-shell, spaced, hollow, laterally-perforated blocks arranged in the path of such remaining products, means constructed to 5 intermingle air with such remaining products during their passage through said blocks, and a damper disposed in the passage and constructed to direct such remaining prod-

ucts either through the boiler-tubes or along its shell. 10

In testimony whereof, I affix my signature, in the presence of two subscribing witnesses.

CHARLES SCHWEIZER.
